UNITED STATES PATENT OFFICE.

JAMES GORDON, OF CHICAGO, ILLINOIS.

COMBINED LIQUOR COOLER AND HOLDER.

SPECIFICATION forming part of Letters Patent No. 415,777, dated November 26, 1889.

Application filed March 11, 1889. Serial No. 302,804. (No model.)

To all whom it may concern:

Be it known that I, JAMES GORDON, a citizen of the United States, residing at Chicago, in the county of Cook and State of Illinois, 5 have invented a certain new and useful Improvements in a Combined Liquor Cooler and Holder, (Case 1,) of which the following is a full, clear, concise, and exact description, reference being had to the accompanying drawings, forming a part of this specification.

My invention relates to wine-coolers; and its object is to provide a cheap and convenient stand for holding the bottles, so that they shall be kept near the ice and yet at the same 15 time be readily accessible.

My invention consists in a revolving holder provided with a central opening for the ice, and pockets arranged about the circumference of the same adapted to hold the bottles 20 containing the liquors, the ice-chamber being provided with a ventilated drip-tube extending upwardly to about the center of the same and below into a tank adapted to receive the water formed by the melting of the ice.

25 My invention will be readily understood by reference to the accompanying drawings, in which—

Figure 1 is a detailed elevation, partly in section, of a liquor-cooler embodying my invention. Fig. 2 is a plan view thereof upon section-line xx of Fig. 1.

Like parts are indicated by similar letters of reference throughout the different figures.

The central chamber a is shown filled with 35 ice. About this chamber are arranged the pockets b c d e f g h i . Each pocket is adapted to hold a single bottle. Thus bottle k is shown in place in pocket b . Bottles containing various kinds of liquor may be placed in the 40 different pockets, as desired. Projecting upwardly into the center of the ice-chamber and below to the bearing in the bottom of the tank

is provided the perforated tube, which serves as a drip-outlet for the water from the ice-chamber and as a central pivotal support for 45 the revolving holder.

My liquor-cooler as thus constructed is cheap and convenient, and especially adapted to be placed upon the bar or in any convenient position, so that the different kinds of 50 liquor will be kept cool and at the same time readily accessible.

My invention admits of various modifications that will readily suggest themselves to those skilled in the art, and I therefore do 55 not limit myself to the precise details of construction shown.

Having thus described my invention, I claim as new and desire to secure by Letters Patent—

1. The combination, with the revolving 60 holder provided with a central ice-chamber and pockets about the same adapted to receive bottles, of a tank below the holder, and a perforated pivot-tube projecting upwardly into the ice-chamber and downwardly into a bearing provided in the tank, substantially as and for the purpose specified.

2. The combination, with the revolving holder provided with a central ice-chamber and pockets about the same adapted to receive 70 the bottles, of a tank below the holder, and a ventilated drip extending upwardly into the ice-chamber and downwardly into the tank, the holder being supported upon the tank above the same and adapted to be revolved 75 to bring any pocket to the front, substantially as and for the purpose specified.

In witness whereof I hereunto subscribe my name this 6th day of March, A. D. 1889.

JAMES GORDON.
